UNITED STATES PATENT OFFICE.

JOHN PETTY, OF LEBANON, PENNSYLVANIA, ASSIGNOR TO JO PET, INC., OF LEBANON, PENNSYLVANIA, A CORPORATION OF PENNSYLVANIA.

METHOD OF SECURING STAY RODS TO PLATES.

Application filed October 1, 1927. Serial No. 223,307.

My invention relates to the construction of boilers and the like in which stay rods are employed and has for its object to provide an improved method for securing the stay rod to a plate, by employing which, a projecting end of the rod extending through a hole in the plate can be formed into a rivet head resting against the outside of the plate without subjecting the portion of the rod 10 lying in and beyond the hole to the risk of distortion and by means of which the rivet head formed on the rod is maintained in tight contact with the outer face of the plate. My improved method consists in inserting the rod in the plate so that its end 15 will project on the outside thereof to a sufficient extent to provide material for the formation of a rivet head, then securing the rod to one side of the plate, preferably the 20 inside thereof, by means of an electric weld or similar fused union forming not only a sufficiently secure attachment between the parts but also as a conductor for heat between the rod and the plate, then heating 25 the projecting end of the rod to a forging temperature and forging it into a rivet head against the outside of the plate. My invention will be best understood as further described in connection with the drawings in 30 which

Figure 1 represents a corner of a boiler with a diagonal stay rod, the upper end of which is secured to the shell by the means described in my prior Patent 1,557,084 of 35 October 13, 1925, while the lower end of the stay rod is shown as projecting through a hole in the boiler head.

Figure 2 is a fragmentary view showing the next stage of my method, and

40 Figure 3, a fragmentary view showing the completion of the attachment between the stay rod and the boiler head.

45 A indicates the head of the boiler; B, its shell. C is the stay bolt, the upper end of which is formed as described in my former patent, with the head D and a rivet forming projection D¹ extending through the shell and formed into a rivet head D². In carry-

ing out my new method, I project the end E of the stay rod through a hole A¹ in the sheet to which it is to be attached and I then place a wire F in near contact with the inner face of the plate A and the adjacent portions of the stay rod and form a fused union, as indicated at F¹ in Fig. 2, uniting 50 the stay bolt to the inner face of the plate. I then heat the projecting end E of the stay rod to a forging temperature and forge it down against the outer face of the plate to 55 the form of a rivet head, as indicated at E¹ in Fig. 3.

The fused union formed between the stay bolt and the sheet through which it passes, 60 serves the purpose of sufficiently uniting the plate and stay bolt to hold them in correct 65 position while the rivet head E¹ is being formed against the outer face of the plate. It also performs the function of forming an 70 efficient heat conducting connection between the stay and the plate so that the heating of the end E of the stay rod does not result in unduly heating the inner portion of the stay, the heat being conducted from the heated 75 end of the stay rod to the plate and thence dissipated by radiation to a sufficient extent to prevent the over-heating of the stay and the consequent risk of deforming it during the heating and forging operations.

My method has the additional advantage 80 in that the stay being secured to the inner face of the plate and a rivet head resting on the outer face of the plate, the cooling of 85 the end of the stay after the formation of the rivet tends to draw the rivet head tightly against the outer face of the plate.

Having now described my invention, what 85 I claim as new and desire to secure by Letters Patent, is:

1. The method of securing a stay rod to a sheet metal plate which consists in inserting the stay rod in a hole in the plate to a position in which its end will project beyond the outer surface of the plate to a sufficient extent to be formed into a rivet head, then securing the rod to one side of the plate by 90 a fused union, then heating the projecting 95

end of the rod to forging temperature and forging it into a rivet head against the outer face of the plate.

2. The method of securing a stay rod to a sheet metal plate which consists in inserting the stay rod in a hole in the plate to a position in which its end will project beyond the outer surface of the plate to a sufficient ex-

tent to be formed into a rivet head, then securing the rod to the inner side of the plate by a fused union, then heating the projecting end of the rod to forging temperature and forging it into a rivet head against the outer face of the plate. ¹⁰

JOHN PETTY.
